UNITED STATES PATENT OFFICE.

BERT G. GOBLE, OF TULSA, OKLAHOMA.

INFLATABLE TIRE.

Application filed March 17, 1921. Serial No. 453,001.

To all whom it may concern:

Be it known that I, BERT G. GOBLE, a citizen of the United States of America, residing at Tulsa, in the county of Tulsa 5 and State of Oklahoma, have invented certain new and useful Improvements in Inflatable Tires, of which the following is a specification.

This invention relates to certain new and 10 useful improvements in inflatable tires and more particularly to the inner tubes therefor of the style, the material of which is under compression, instead of under tension, when the tube is encased and inflated.

15 Inner tubes of this type have been provided with one or more annular continuous depressions or folds, and the external diameter of the tube is greater than the internal diameter of the casing with which it is to be used, so that when the tube is filled with 20 air under pressure, said tube is forced into snug contact with the inner face of the casing throughout, and the tube is thereby placed under transverse compression. Tubes 25 of this character which have heretofore been devised, have been extremely hard to place within the casing, this being caused in some instances by the provision, in addition to side folds or depressions, of a tread fold or 30 depression so that the folds are necessarily based upon abrupt curvatures which combine to provide a somewhat truss-like structure making the tube very rigid so that it will not readily give or flex when being 35 placed within the casing. This rigidity is pronounced when it is considered that the compression type of tube is necessarily of considerable thickness of material.

In addition to the fact that the provision 40 of more than two folds in a tube of this character, provides undesirable rigidity of the tube, it also gains no additional compression because of the fact that at least one of the three folds may not be practically 45 made of sufficient depth to gain such additional compression. In other words, the provision of the folds is to primarily obtain a greater external diameter for the tube than the internal diameter of the casing, 50 and in order to accomplish this, the depth of the folds must be great enough to give the tube a greater length at the fold than the corresponding surface on the inside of the casing. There is not sufficient room for 55 three sufficiently deep folds in a tube of this character unless the folds are based upon

curves so abrupt as to make manufacture of the same entirely impractical, the manufacture of a tube of uniform thickness being at least extremely hard to accomplish 60 where very abrupt curves are encountered.

In such cases where only a single and a tread depression or fold has been used, the tube has a normal circular cross section, and extraneous means is relied upon for holding 65 the tube in an abnormal condition with the fold portion tending to move outwardly into flat contact with the inner face of the casing when the tube is released. By the use of such holding means, the tube is forced 70 into a very broad cross sectional dimension, and the tube is then of very abrupt curvature at the sides and wider than the casing so that placement of such a tube within the 75 casing entails considerable skill and arduous labor.

It has been also proposed to provide a pair of folds, one located at each side of the tread portion of the casing but outwardly of the axial center line of the tube. It has been 80 found, however, that a tube so constructed does not have much more flexibility than the before mentioned prior art tube and therefore the operation of placing the tube within the casing is also tedious. In addition to this, 85 when the folds are provided entirely outwardly of the axial center line of the tube, the fold portions of the tube are necessarily placed under circumferential stretch when inflated to such an extent as to be detrimental 90 under running conditions.

In the present invention, the above defects are overcome by the provision of a compression tube molded to have a normal form with only two depressions or folds located at 95 the sides of the tube and intersecting the axial center line of the tube so that the tube is highly flexible for being readily placed within the casing and so that no material circumferential stretch results, the little circumferential stretch in the folds that does take place being entirely away from the tread portion of the tube where punctures most ordinarily occur. Also, the folds of the present tube are based upon long symmetrical curves instead of abrupt ones so that the flexibility of the tube is thereby enhanced and stretching of the tube at the insides of the curves, is reduced to a minimum, when the tube is changed in shape by 105 inflation.

The present invention also contemplates

molding of the tube so as to normally be spaced from the rim and the bead portion of the casing for permitting placement of the tire upon the rim and insertion of the 5 fastening rings of the rim with much greater ease.

With the above general objects in view, and others that will become apparent as 10 the nature of the invention is better understood, the same consists in the novel form, combination and arrangement of parts hereinafter more fully described and shown in the accompanying drawings, in which like reference characters designate corresponding 15 parts throughout the several views.

In the drawings,

Figure 1 is a transverse section through a tire and rim and showing the present inner tube seated within the casing prior to the 20 admission of air under pressure to the interior of the tube,

Figure 2 is a view similar to Figure 1 showing the inner tube of the latter figure inflated by air under pressure so as to place 25 the tube under compression, this Figure 2 being drawn on a smaller scale,

Figure 3 is a view similar to Figure 1 of a modified form of the invention, and

Figure 4 is a view similar to Figure 2 of 30 the device shown in Figure 3.

Referring more in detail to the several views, and particularly to Figures 1 and 2, 5 indicates the present inner tube whose internal diameter is greater than the internal 35 diameter of the casing 6 with which it is to be used, and whose circumferential length at its inner periphery as at 7, is normally greater than the circumferential length of the rim 8 which carries the tire, the difference in length at this point being sufficiently 40 great to leave a material space as at 9 between the inner periphery of the tube and the usual protecting band or flap 10 which is placed upon the rim so as to protect the inner portion of the tube from rust and other difficulties normally encountered. The 45 tube 5 is also molded at opposite sides of its inner periphery 7 so as to normally leave spaces as at 11 between the tube and the bead portions 12 of the casing 6 so that said bead portions may readily yield toward each other for permitting ready insertion 50 of the fastening rings 13 and 14 commonly found upon the conventional detachable or demountable rims now in use, and which fastening rings ordinarily are quite hard to 55 place in position or to remove.

The tube is also molded so that substantially its entire tread portion 15 conforms 60 to the adjacent inner surface of the casing 6 so that no inward folds or fold is provided at the tread of the tube and the flexibility of the tube is thereby not impaired. As clearly shown in Figure 1, the tube 5 is 65 molded with opposed annular folds or de-

pressions 16 in the sides thereof sufficiently near the inner periphery of the tube to intersect the axial center line A—A of the latter and to be entirely away from the tread portion of the tube, the folds 16 being based upon long symmetrical curves calculated to give high flexibility for permitting ready insertion of the tube within the casing.

The form of the invention shown in Figure 3 is similar to that shown in Figure 1 75 with the exception that the tread portion 15' of the tube 5' is molded on an arc or curvature of lesser radius than that of the adjacent inner surface of the casing 6' so that if the tube 5' were actually centered within 80 the casing as shown in Figure 3, a uniform space as at 17 would be left between the tread portion of the tube and the casing. This spacing at the tread portion is calculated to render insertion of the tube within 85 the casing additionally easier. In this form of the invention, the side folds are denoted by the numeral 16', the axial center line of the tube at A'—A', the inner periphery by 7', the rim by 8', the protecting ring by 90 10' and the space between the periphery 7' and the ring or band 10' by 9', and the fastening rings by 13' and 14'. The spacing between the inner side portions of the tube and the bead portions of the casing are indicated by the numeral 11' while the bead portions of the casing are indicated by the numeral 12'. Thus it will be seen that the entire tube, if centered in the casing in deflated condition, would be entirely spaced 100 from said casing and with this normal relative size and shape between the tube and casing, insertion of the tube in the casing may be easily accomplished.

As is usual in this general type of tube, 105 and as shown clearly in Figures 2 and 4, the tube assumes a flat contact with the inner surface of the casing throughout when the tube is placed under inflation pressure and when this takes place, the compression of 110 the tube is had.

It is believed that the construction and operation as well as the advantages of the present invention will be readily understood and appreciated by those skilled in the art. 115 Reservation is made of the right to make such specific changes in contour and arrangement as may fall within the spirit and scope of the invention as expressed in the accompanying claims.

What is claimed as new is:

1. As a means for pneumatically supporting a casing or shoe for vehicle service, an inner tube formation having a normal definite and predetermined cross sectional contour when out of a shoe and free from pressure application and a cross sectional configuration varied from such normal configuration when inflated within the shoe, said shoe formation having its walls of a 130

thickness such as to maintain such normal configuration when free from pressure application to the formation, the normal configuration of such formation presenting the 5 tread zone of the formation as of a curvature substantially complementary to the internal face of the tread zone of the shoe, such normal configuration presenting the side walls of the formation as annular de-
10 pressions, the depth of the depressions on a cross section of the formation being such as to cause the inner face of the depression wall at the bottom of the depression to approach a plane of the formation that ex-
15 tends parallel to a side of the formation when inflated and which extends central of the formation, the bottoms of the depressions on a cross section of the formation each intersecting a line extending approxi-
20 mately through the axis of the formation transversely of such plane, the walls of each depression generally diverging from the depression bottom and joining the portions of the formation beyond the de-
25 pression, the bottoms of the depressions and the joining portions extending on curved lines free from abrupt changes in direction,

whereby the formation is insertible within the shoe and the cross sectional wall of the formation is inflatable to place it in facial 30 contact with the positioned shoe, the depth of the depressions being such as to place the wall material of the formation under compression in the direction of its cross sec-
35 tional length and substantially throughout such length.

2. An inner tube formation of the type of claim 1 characterized in that the length of the radius producing the outer face of the tread zone of the formation is less than 40 the length of the radius producing the inner face of the tread zone of the shoe, whereby the formation when symmetrically positioned within the shoe prior to the formation inflation will present a space of material ex-
45 tent between the opposing faces of the respective tread zones of the shoe and formation, inflation of the formation serving to eliminate such space and place the opposing face portions of the tread zones in facial contact. 50

In testimony whereof I affix my signature.

BERT G. GOBLE.
